[57] CLAIM

The ornamental design for a adjustable copy holder for attachment to a computer monitor, as shown and described.

DESCRIPTION

FIG. 1 is a top, left front perspective view of an adjustable copy holder for attachment to a computer monitor showing my new design, the computer monitor being depicted by means of broken lines for illustrative purposes only and forming no part of the claimed design; FIG. 2 is a front elevational view thereof; FIG. 3 is a rear elevational view thereof; FIG. 4 is a top plan view thereof; FIG. 5 is a bottom plan view thereof; FIG. 6 is a right side elevational view drawn to an enlarged scale; and, FIG. 7 is a left side elevational view drawn to the scale of FIG. 6. The FIG. 1 view has been drawn to a reduced scale with respect to FIGS. 2 through 7.
